US00D807858S

(12) **United States Design Patent** (10) Patent No.: **US D807,858 S**
Ryu et al. (45) Date of Patent: ** Jan. 16, 2018

(54) **BLUETOOTH EARSET COMMUNICATION EQUIPMENT**

(71) Applicant: **LG ELECTRONICS INC.**, Seoul (KR)

(72) Inventors: **SeoungHoon Ryu**, Seoul (KR); **Jinwan Bae**, Seoul (KR); **Jeeyoung Yeon**, Seoul (KR); **Joe Hyun**, Seoul (KR); **Junseop Lee**, Seoul (KR)

(73) Assignee: **LG ELECTRONICS INC.**, Seoul (KR)

(**) Term: **15 Years**

(21) Appl. No.: **35/501,854**

(22) Filed: **May 9, 2016**

(80) **Hague Agreement Data**

Int. Filing Date: **May 9, 2016**

Int. Reg. No.: **DM/091334**

Int. Reg. Date: **May 9, 2016**

Int. Reg. Pub. Date: **Nov. 11, 2016**

(30) **Foreign Application Priority Data**

Nov. 27, 2015 (KR) 30-2015-0060237

(51) LOC (11) Cl. **14-01**

(52) U.S. Cl.

USPC **D14/205**

(58) **Field of Classification Search**

USPC D14/205; D3/218

CPC H04M 1/05
